AUTOMATIC DOOR LOCK

Charles L. Crooks, Pueblo, Colo.

Application August 22, 1938, Serial No. 226,085

11 Claims. (Cl. 292—25)

This invention relates to a locking latch more particularly designed for use upon automobile and other vehicular doors.

The principal object of the invention is to provide a single and highly efficient lock which will automatically latch itself when the door is closed in such a way that it cannot possibly be opened by an unauthorized party; which when closed will be absolutely secure against rattling or vibration; and which can be locked by a single turn of the inside handle.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawings and throughout the description.

In the drawings:

Fig. 1 is a fragmentary view illustrating the improved lock in position in a typical automobile door.

Fig. 2 is an edge view of the latch proper.

Fig. 3 is an inside face view of the latch.

Fig. 4 is a vertical section therethrough, taken on the line 4—4, Fig. 3.

Fig. 5 is a detail section taken on the line 5—5, Fig. 4.

Fig. 6 is a face view of the latch mechanism with the cover plate removed. This view is taken on the line 6—6, Fig. 8, and illustrates the latch in the closed, locked position.

Fig. 7 is a similar view illustrating the latch in the releasing position.

Fig. 8 is a cross section taken on the line 8—8, Fig. 6.

Fig. 9 is a detail section taken on the line 9—9, Fig. 8.

Figs. 10 and 11 are vertical sections taken on the lines 10—10 and 11—11, respectively, Fig. 6.

Fig. 12 is a detail section through the inside handle mechanism.

Fig. 13 is a detail section through the inside handle mechanism taken on the line 13—13, Fig. 12.

Fig. 14 is a detail view of the inside handle spring housing.

Fig. 15 is a section through the spring housing taken on the line 15—15, Fig. 14.

Fig. 16 is a detail view of the locking block.

In Fig. 1 a typical automobile door is indicated at 10 with its frame at 11. The casing in which

the improved latch mechanism is contained is indicated at 12. The latch may be operated from an external door handle of any desired type which may contain a key actuated lock if desired. The shank of such an external door handle is indicated at Fig. 3 at 13. The latch may also be operated from an inside handle 14.

The striker plate of the latch, indicated at 15, is attached to the frame 11 in the usual manner. This plate carries a spear-shaped keeper raised, 10 embossed or otherwise projected outwardly on its surface. The sides of the keeper are notched as shown at 16 and its point is directed toward the outside of the automobile.

Two similar, oppositely-positioned L-shaped 15 locking bolts 17 are pivoted on pivots 18 within the housing 12 in a position to be engaged by the keeper 16, the housing being cut away at this point to allow entrance of the keeper. The bolts 17 terminate in over-lapped rearward extremities 19 and are constantly urged to the closed position at their forward extremities by means of compression springs 20.

A slide plate 21 is slidably mounted against one face of the casing. The slide plate 21 carries 25 a pointed, wedging boss 22 positioned between the two bolts 17 so that as it slides inwardly, it will contact the rear extremities 19 thereof to force the forward extremities together. The plate 21 is bifurcated at its inner edge to fit around a sliding, 30 actuating member 23. The actuating member 23 contacts the rear extremities 19 of the bolts 17 and, when forced against these rearward extremities, causes them to swing over each other to separate the forward extremities, as shown in 35 Fig. 7.

The actuating member 23 is moved by a cross lever 24 which is secured on a latch shaft 25. The sliding plate 21 is prevented from being moved until the cross lever is actuated by means of a latch 40 lever 26, one extremity of which carries a flange 27 which over-hangs the outer end of one of the guide members 22 and which is swung by means of a spring 28 into the path of the plate 21 to prevent the latter from moving.

The lever 26 is notched, as shown at 29, to receive the extremity of a lifting tongue 30 which is formed on the cross lever 24. In the locked position of Fig. 6, the tongue rests in the notch. The first movement of the shaft 25 and the lever 50 24, however, causes this tongue to swing forwardly and lift the flanged extremity of the locking lever 26 out of the path of movement of the plate 21 so that continued movement of the lever 24 may force the actuating plate 23 outwardly to 55

separate the bolts 17, as shown in Fig. 7. The lever 24 is returned to its original position by means of a suitable spring 31. The sliding plate 21 is retained in the projected position by means 5 of a ball detent 32 which is actuated by means of a spring 33 against the side of the plate 21 where a receiving notch 34 is provided.

The shaft 25 may be rotated in any desired manner depending upon the particular installation of the latch. As illustrated, a two-point cam 10 35 is secured on the shaft 25 and a handle shaft 36 carrying the outside door member is rotatably mounted across the cam 35. The shaft 36 carries a fixed first sleeve 37 from which a first cam 15 actuating lever 38 projects so that as the outer handle is turned, the actuating lever will be swung against the cam 35 to rotate the shaft 25 and actuate the bolts 17.

The shaft 36 also carries a loose sleeve 39 from 20 which a second cam actuating lever 40 projects. This sleeve is rotated from the inner door handle 14 and causes the second actuating lever 40 to contact the opposite extremity of the cam 35 to also actuate the bolts 17. The sleeve 39 is actuated from the inner handle 14. Projecting from the latter sleeve is an L-shaped arm 41 having a slotted hole 42 for receiving a screw 43 which is threaded into a locking block 44. The locking block 44 is carried upon a locking plunger 45 30 which projects rigidly from the block through a guide tube 46 into the latch casing 12. The locking plunger 45 is so positioned, as shown in Fig. 1, that when projected into the casing, it will be in the path of movement of the rear extremities 35 of the bolts 17 and also in the path of movement of the plate 21 so that none of these parts can be moved until the locking plunger 45 is withdrawn by actuation of the inside handle 14 to move the locking block 44 to the left as shown 40 in Fig. 2. During the locking movement of the block 44, the screw 43 travels in the slotted hole 42.

The block 44 is connected by means of connecting bar 47 to a fan-shaped lever 48 mounted on an inner handle shaft 49 which carries the inner handle 14. A detent spring 50 constantly urges a ball detent 51 against the lever 48, the latter being provided with two ball receiving depressions 52 and 53. The connecting bar 47 is constantly urged toward the locked position by 50 means of a spring 54 which forces a plunger 55 against a projection 56 on the bar 47. The spring and plunger mechanism is contained in a housing 57 mounted alongside of the bar 47.

Operation

55 When the door is open, the latch mechanism is in the position shown in Fig. 6 with the exception that the plate 21 is in the forward position of Fig. 7 where it is held by the detent 32. As the door swings shut, the points of the keeper 16 enter between the bolts 17 wedging them outwardly. It then strikes the wedge boss 22 forcing the plate 21 inwardly. This causes the point of the wedge boss to force the hooked extremities of the bolts apart so as to swing the other extremities into the notches 58 of the keeper 16, as shown in Fig. 6. The locking lever 27 then snaps in front of the plate 21 and locks the bolts 17. The bolts can be released and opened by simply turning the outer handle shaft 36 which rotates the shaft 25 to release the lever 26 and move the bolts to the position of Fig. 7. It can be similarly actuated by moving the inner handle 14 to pull the connecting rod 47 away from the latch and swing the lever 40 against the cam 35.

The latch may be locked against opening by swinging the inside handle to the left or "lock" position which causes the connecting bar 47 to push the locking block 44 toward the casing 12 so that its locking plunger 45 will enter the casing to the locking position of Fig. 6.

We, therefore, have three positions of the inside handle lever 14: straight downward for the inactive or "close" position; to the right to open the door; and to the left to lock the door.

10 While a specific form of the improvement has been described and illustrated herein, it is desired to be understood that the same may be varied, within the scope of the appended claims, without departing from the spirit of the invention.

15 Having thus described the invention, what is claimed and desired secured by Letters Patent is:

1. In a door latch mechanism of the type having a pair of pivoted hooked end bolts adapted to engage an arrowhead type of keeper, a means for engaging and disengaging said bolts with said keeper comprising: an inner extremity on each bolt, said extremities being turned toward each other in overlapped relation; a bolt closing member positioned for movement between said bolts to contact the overlapped extremities thereof to force the latter apart so as to force the forward extremities towards each other; and a bolt opening member positioned beyond the overlapped extremities so that it may contact and force the latter together so as to separate the forward extremities thereof; and means for causing said closing member to release said bolts as said opening member opens them.

20 2. In a door latch mechanism of the type having a pair of pivoted hooked end bolts adapted to engage an arrowhead type of keeper, a means for engaging and disengaging said bolts with said keeper comprising: an inner extremity on each bolt, said extremities being turned toward each other in overlapped relation; a bolt closing member positioned for movement between said bolts to contact the overlapped extremities thereof to force the latter apart so as to force the forward extremities toward each other; and a bolt opening member positioned beyond the overlapped extremities so that it may contact and force the latter together so as to separate the forward extremities thereof; and means for causing said closing member to release said bolts as said opening member opens them.

25 3. In a door latch mechanism of the type having a pair of pivoted hooked end bolts adapted to engage an arrowhead type of keeper, a means for engaging and disengaging said bolts with said keeper comprising: an inner extremity on each bolt, said extremities being turned toward each other in overlapped relation; a bolt closing member positioned for movement between said bolts to contact the overlapped extremities thereof to force the latter apart so as to force the forward extremities towards each other; a stop member; and means for projecting said stop member into the path of movement of said bolts to prevent the latter from releasing said keeper until desired.

30 4. In a door latch mechanism of the type having a pair of pivoted hooked end bolts adapted to engage an arrowhead type of keeper, a means for engaging and disengaging said bolts with said keeper comprising: an inner extremity on each bolt, said extremities being turned toward each other in overlapped relation; a bolt closing member positioned for movement between said bolts

to contact the overlapped extremities thereof to force the latter apart so as to force the forward extremities toward each other; and a bolt opening member positioned beyond the overlapped extremities so that it may contact and force the latter together so as to separate the forward extremities thereof, said closing member being positioned in the path of said opening member so that as the latter moves to the opening position it will force the closing member away from said overlapped extremities.

5. In a door latch mechanism of the type having a pair of pivoted hooked end bolts adapted to engage an arrowhead type of keeper, a means 15 for engaging and disengaging said bolts with said keeper comprising: an inner extremity on each bolt, said extremities being turned toward each other in overlapped relation; a bolt closing member positioned for movement between said bolts 20 to contact the overlapped extremities thereof to force the latter apart so as to force the forward extremities towards each other; and a bolt opening member positioned beyond the overlapped extremities so that it may contact and force the latter together so as to separate the forward extremities thereof; an actuating shaft; and an actuating lever projecting from said shaft to actuate said opening means.

6. In a door latch mechanism of the type having a pair of pivoted hooked end bolts adapted to engage an arrowhead type of keeper, a means 30 for engaging and disengaging said bolts with said keeper comprising: an inner extremity on each bolt, said extremities being turned toward each other in overlapped relation; a bolt closing member positioned for movement between said bolts to contact the overlapped extremities thereof to force the latter apart so as to force the forward extremities towards each other; a bolt opening 35 member positioned beyond the overlapped extremities so that it may contact and force the latter together so as to separate the forward extremities thereof; an actuating shaft; and an actuating lever projecting from said shaft to 40 actuate said opening means; a locking lever positioned to swing into the path of movement of said opening means to prevent the latter from moving to the opening position; and releasing means actuated by said actuating lever for swinging said locking lever from the path of said opening 45 means before the latter actuates said bolts.

7. In a door latch mechanism of the type having a pair of pivoted hooked end bolts adapted to engage an arrowhead type of keeper, a means for 50 engaging and disengaging said bolts with said keeper comprising: an inner extremity on each bolt, said extremities being turned toward each other in overlapped relation; a bolt closing member positioned for movement between said bolts 55 to contact the overlapped extremities thereof to force the latter apart so as to force the forward extremities towards each other; and a bolt opening member positioned beyond the overlapped extremities so that it may contact and force the latter together so as to separate the forward extremities thereof; a stop member; means for projecting said stop member into a position to prevent said opening member from operating; and means for actuating said opening member 60 from the withdrawing movement of said stop member.

8. In a door latch mechanism of the type having a pair of pivoted hooked end bolts adapted to engage an arrowhead type of keeper, a means 65 for engaging and disengaging said bolts with

said keeper comprising: an inner extremity on each bolt, said extremities being turned toward each other in overlapped relation; a bolt closing member positioned for movement between said bolts to contact the overlapped extremities thereof to force the latter apart so as to force the forward extremities towards each other; and a bolt opening member positioned beyond the overlapped extremities so that it may contact and force the latter together so as to separate the forward extremities thereof; an actuating shaft; and an actuating lever projecting from said shaft to actuate said opening means; and means for rotating said shaft from both sides of said door.

9. In a door latch mechanism of the type having a pair of pivoted hooked end bolts adapted to engage an arrowhead type of keeper, a means 15 for engaging and disengaging said bolts with said keeper comprising: an inner extremity on each bolt, said extremities being turned toward each other in overlapped relation; a bolt closing member positioned for movement between said bolts to contact the overlapped extremities thereof to force the latter apart so as to force the forward extremities towards each other; and a bolt opening member positioned beyond the overlapped extremities so that it may contact and force the latter together so as to separate the forward extremities thereof; an actuating shaft; and an actuating lever projecting from said shaft to actuate said opening means; a cam mounted 20 on said shaft; a handle shaft rotatable mounted across said cam; a cam actuating lever carried by said handle shaft, so that as the handle shaft is rotated the lever will contact said cam and rotate the said actuating shaft; a handle on said handle shaft, said handle being positioned on one side of said door; a second cam actuating lever loosely mounted on said handle shaft; a handle on the other side of said door operatively 25 connected with said second cam actuating lever so that as the second handle is turned, the actuating shaft will be rotated.

10. In a door latch mechanism of the type having a pair of pivoted hooked end bolts adapted to engage an arrowhead type of keeper, a means 30 for engaging and disengaging said bolts with said keeper comprising: an inner extremity on each bolt, said extremities being turned toward each other in overlapped relation; a bolt closing member positioned for movement between said bolts to contact the overlapped extremities thereof to force the latter apart so as to force the forward extremities towards each other; and a bolt opening member positioned beyond the overlapped extremities so that it may contact and force the latter together so as to separate the forward extremities thereof; an actuating shaft; and an actuating lever projecting from said shaft to 35 actuate said opening means; a cam mounted on said shaft; a handle shaft rotatable mounted across said cam; a cam actuating lever carried by said handle shaft, so that as the handle shaft is rotated the lever will contact said cam and rotate the said actuating shaft; a handle on said handle shaft, said handle being positioned on one side of said door; a second cam actuating lever 40 loosely mounted on said handle shaft; a handle on the other side of said door operatively connected with said second cam actuating lever so that as the second handle is turned, the actuating shaft will be rotated; a locking block; a locking plunger carried by said block, said plunger positioned so that when projected into the casing it 45 will be in the path of movement of the said rear 50 door.

extremities of said hooked end bolts; and means connected to the second handle only for moving said plunger into the locking position.

- 5 11. In a door latch mechanism of the type having a pair of pivoted hooked end bolts adapted to engage an arrowhead type of keeper, a means for engaging and disengaging said bolts with said keeper comprising: an inner extremity on each bolt, said extremities being turned toward each other in overlapped relation; a bolt closing member positioned for movement between said bolts to contact the overlapped extremities thereof to force the latter apart so as to force the forward extremities towards each other; and a bolt opening member positioned beyond the overlapped extremities so that it may contact and force the latter together so as to separate the forward extremities thereof; an actuating shaft; an actuating lever projecting from said shaft to 15 actuate said opening means; a cam mounted on said shaft; a handle shaft rotatable mounted

across said cam; a cam actuating lever carried by said handle shaft, so that as the handle shaft is rotated the lever will contact said cam and rotate the said actuating shaft; a handle on said handle shaft, said handle being positioned on one side of said door; a second cam actuating lever loosely mounted on said handle shaft; a handle on the other side of said door operatively connected with said second cam actuating lever so that as the second handle is turned, the actuating shaft will be rotated; a locking block; a locking plunger carried by said block, said plunger positioned so that when projected into the casing it will be in the path of movement of the said rear extremities of said hooked end bolts; means connected to the second handle only for moving said plunger into the locking position; and means for removing said plunger from the locking position prior to the opening of the lock.

CHARLES L. CROOKS.
